Primary Examiner — Omeed Agilee*Assistant Examiner* — David Truong(74) Attorney, Agent, or Firm — Dunlap Bennett & Ludwig, PLLC(57) CLAIM

The ornamental design for a communion box, as shown and described.

DESCRIPTION

FIG. 1 is a top front perspective view of a communion box, showing my new design;

FIG. 2 is a front elevation view thereof;

FIG. 3 is a rear elevation view thereof;

FIG. 4 is a right-side elevation view thereof with a left-side elevation view being a mirror image thereof;

FIG. 5 is a top plan view thereof; and,

FIG. 6 is a bottom plan view thereof.

The broken lines shown in the drawings depict environmental subject matter and form no part of the claimed design.

1 Claim, 4 Drawing Sheets(56)
